UNITED STATES PATENT OFFICE.

WILLIAM E. CRIST, OF BALTIMORE, MARYLAND, ASSIGNOR OF ONE-HALF TO GEORGE E. CRIST, OF SPARROWS POINT, MARYLAND.

VENTILATED JOURNAL-BOX.

1,251,183.

Specification of Letters Patent. Patented Dec. 25, 1917.

Original application filed December 9, 1911, Serial No. 664,769. Divided and this application filed September 19, 1912. Serial No. 721,139.

To all whom it may concern:

Be it known that I, WILLIAM E. CRIST, a citizen of the United States, residing in Baltimore city and State of Maryland, have 5 invented a new and useful Improvement in Ventilated Journal-Boxes, of which the following is a specification.

This invention relates to improvements in 10 ventilated journal boxes, and more particularly to those used on railway locomotive tenders, passenger, freight and other car boxes which have the journal boxes located on the axles outside of the wheels, but it will be understood that the invention may be 15 applied to other forms of journal boxes, without departing from the spirit of the invention.

An object of the invention is to provide 20 means for ventilating the interior of journal boxes of the type above indicated which will permit or cause a free circulation of air within the journal box, the heated or foul air within the box being constantly replaced by cooler air from the atmosphere, this circulation being caused by the increased pressure 25 of the atmosphere on one side of the journal box, namely, the advance or forward side when the train is moving, and the decreased pressure of the atmosphere on the 30 rear side of the journal box.

Another object of the invention is to provide 35 means for ventilating the interior of journal boxes in such a way that the air will circulate about and around the end and undersides of the axle journals, thus cooling the axle journals on their outer surfaces, as contradistinguished from former types of 40 ventilated journal boxes where the air is passed through perforations in the axles.

Still another object of the invention is to 45 provide means for ventilating the interior of journal boxes which are applied to the lid or cover of the journal box, so that the improved form of lid or cover may be applied to journal boxes already in use by merely replacing the old, plain form of lid.

The invention furthermore consists in the 50 improvements in the parts and devices and in the novel combinations of parts and devices herein shown, described or claimed.

In the drawing forming a part of this specification, Figure 1 is a side elevation of a journal box showing my improvements in connection therewith. Fig. 2 is an elevation

of the lid or cover of the journal box detached. Fig. 3 is a sectional view, taken substantially on the line 3—3 of Fig. 2, and Fig. 4 is an enlarged, detail, sectional view, taken substantially on the line 4—4 of Fig. 2.

In the drawing, 10 denotes the journal box proper which, as shown, is provided with the usual lugs 11 and 12 on the sides thereof by means of which the journal box may be bolted to the car truck. The cover 65 or lid 13, as shown in the drawing, is pivoted at 14 to the journal box, but as will be obvious to those skilled in the art, the lid or cover may be otherwise secured to the journal box than as shown. The lid is provided 70 with a raised or outstanding portion 15, which is provided with a pair of air passageways 16, 16, separated by a partition or rib 16^a, each having a substantially vertical, inlet orifice 17, said inlet orifices facing in 75 opposite directions so that air will always be forced through the front passageway 16, as shown by the arrows *a*, when the train is moving in the direction indicated by the arrow *b*, depending upon the direction of 80 movement of the car upon which the journal box is mounted. The cover or lid is also provided with a pair of air inlet and outlet orifices 18, 18, each orifice 18 communicating 85 directly with the interior of the journal box, and also by means of passageways 19, 19 with the other air passageways 16, 16. As air is forced through either passageway 16, as shown for instance by the arrows *a*, air 90 will be withdrawn from the interior of the journal box through one of the orifices 18 through the passageway 19 in the manner indicated by the arrows *c*, due to the decreased pressure within the passageway 19 created by the draft of air through the passageway 16. As air is withdrawn from the 95 interior of the journal box through one of the orifices 18, namely the one at the forward side of the journal box, a supply of fresh or cooler air will be drawn into the 100 interior of the journal box through the other orifice 18. In order to prevent sand, dust or other foreign matter from being accidentally drawn into the interior of the journal box, a screen or gauze 20 may be 105 placed in each of the orifices 18, said screens being adapted to be held in place as by means of an expandible loop 21 adapted to

seat in a groove 22 formed in the wall of the orifice, see Fig. 1.

From the foregoing description, it will be seen that so long as the car or train is in motion, a continuous change of air will be produced within the journal box, without liability of sand, dust or other undesirable foreign matter being introduced therein, since all the air which is forced through the 10 passageways 16, which air, of course, is collected from the forward side of the journal box as the car is in motion, passes through the passageways without any of it passing to the interior of the box, and the air which 15 does get to the interior of the box is drawn in from the rear side of the journal box by suction or induced draft.

I have shown and described what I now consider the preferred form of my invention; but it will be apparent that various changes and modifications may be made in the arrangement of the different parts without departing from the spirit of the invention; and all such changes and modifications 25 are contemplated as fall within the scope of the claims appended hereto. *This application is a division of my original application No. 661,769, filed December 19th, 1911, and is serially numbered 80. I claim:*

1. As an article of manufacture a journal box lid adapted for use on railway cars, said lid being provided with an air passageway on the exterior thereof and through which a draft of air is produced when the car is in motion; said lid being provided also with another passageway communicating with the interior of the box and with the first named passageway, whereby the air from the interior of the box is withdrawn by suction induced by said air draft when the car is in motion; substantially as specified.

2. As an article of manufacture, a journal 45 box lid adapted for use on railway cars and provided with a pair of passageways on the exterior of the lid and through each of which a draft of air is adapted to be produced when the car is in motion, said lid being provided also with another pair of passageways each communicating with the interior of the box and with one of the first named passageways, whereby the air from the interior of the box is withdrawn by suction induced by the air draft through either of the first named passageways when the car is in motion, substantially as specified.

3. As an article of manufacture, a journal

box lid having spaced front and back walls, a partition dividing the chamber between them into passageways communicating with the interior of the journal box for inducing atmospheric air and removing the air and gas within the journal box for ventilation.

4. As an article of manufacture, a journal 60 box lid provided with an air inducing passageway and a gas and air removing passageway for the purposes of ventilation, said passageways being located within the confines of the lid.

5. As an article of manufacture, a journal 65 box lid having an internal divided chamber defined by the side walls of the lid, said lid being provided with lateral openings into the parts of said chamber for forming passageways for inducing atmospheric air within the journal box.

6. As an article of manufacture, a journal 70 box lid having front and rear walls, partitions between said walls, said partitions serving to form inlet and outlet passageways to the interior of the journal box and to provide vacuum creating passageways for forcing air through the journal box for ventilation.

7. As an article of manufacture a journal 75 box lid adapted for use on railway cars, provided with an air passageway leading from the interior of the box and with means for directing the atmospheric air set in rapid relative motion by the train movement over said air passage to withdraw the air from the interior of the journal box by suction thus induced.

8. As an article of manufacture a journal 80 box lid having alternately operable air inlet and air outlet passageways, operable when a train provided with said lid is in motion, and provided with means for directing atmospheric air across the forward passageway with respect to the direction of movement of the train to constitute said passageway an outlet passageway by suction induced by the movement of such air across or over said passageway.

9. As an article of manufacture, a journal 85 box lid provided with alternately operable inlet and outlet passageways and with auxiliary suction creating passageways for governing the functioning of the inlet and outlet passageways.
